a bolt 43, nut 44, and washers 45. A suitable dielectric insulating shoe 46 and a bushing 47 are provided to prevent electrical contact between the strip 41 and the bar housing 48. An identical contact element 40 is used in conjunction with the heddles associated with pile yarns 26. The heddles are kept in alignment and under control at the bottom by means of a cable 50 stretched tautly between frame elements 51 and 52 of the loom by means of eye bolts 53, 53 and nuts 54, 54.

In operation, it will be understood that as harnesses 25 and 24 reverse their positions from top to bottom, thereby forming the warp shed, the heddles 36 normally rest on their associated elements 40 so that the biased upper termini 38, 38 of the slots in plates 37, 37 make electrical contacts between strips 41, 41 and the housing 48, 48. However, during this part of the cycle a conditioning circuit, to be described later, is held open. When harness 25, for example, is elevated to its top position, as shown in Fig. 1, the yarns 27 passing through the eye 35 of heddles 36 elevate the heddle and break and hold open the electrical contact between plates 37, 37 and strips 41, 41. At this point the conditioning circuit is closed and, should there be no unelevated heddle 36, the stop mechanism fails to function. However, in the event there is more than a predetermined slack in one of the yarn ends 27 or if one of the ends is broken, the circuit will be completed due to the failure of a heddle 36 to rise, thus stopping the loom. The operation of the second row of heddles 36 through which pile yarns 26 are threaded is identical but works in opposite relationship because there are only two pile yarn harnesses in the showing of Fig. 1.

Where more than two pile yarn harnesses are used as shown in Fig. 2, there may be a condition in which it is desired to operate the harnesses in pairs so that pile yarn harnesses 60 and 61 work together, pile yarn harnesses 62 and 63 work together, and binder warp harnesses 20 and 21 work oppositely in the same manner as shown in Fig. 1. Under these conditions we draw the pile yarns 64 and 65 carried by harnesses 60 and 61 through the slots of stop motion heddles 66 and 67 respectively. It will thus be apparent that heddle 67 carries two pile yarns, namely 65 and 68, whereas heddle 66 carries two pile yarns 64 and 69.

Figs. 3 and 4 show in somewhat greater detail the construction of the contact elements 40 and their relation to the loom structure. Each element 40 is anchored in a loom bracket 75 and 76 by means of setscrews 77, 77. The brackets 76 are in turn secured to portions of the loom frame 78 by means of capscrews 79, 79. In actual practice the plates 37 on the heddles are turned approximately 30° from the long slots 35 as shown in Fig. 7, but this detail is omitted from the showing in Fig. 3 in the interests of clarity.

Referring now to Fig. 8, the electrical sensing circuit for the construction shown in Figs. 1-4 comprises a source of high voltage electrical energy 85 connected to transformer 86 through switch 87. High voltage leads 88 and 89 are tapped into the lines between switch 87 and transformer 86 to supply current to the loom motor 90. The low tension side of transformer 86 connects with a start and stop switch 91 having a start button 92 and a stop button 93. Leads 88 and 89 are carried through two sets of contacts of triple contact relay 94 and the remaining contacts of relay 94 serve as a holding circuit for the relay through leads 95 and 96. In starting, the loom start switch 92 is closed, thereby completing a circuit to coil 97 of relay 94 through leads 96, 98, and 99. This energizes relay 94 to close all three sets of contacts thereof starting motor 90 and closing the holding circuit for relay 94. The holding circuit for relay 94 is carried through the contacts 100 of a normally closed relay 101 through leads 102 and 96. One side of the coil of relay 101 is tapped into lead 102 and the other side is carried through a conditioning switch 103 which is mechanically actuated by means of a timing cam 104 and a cam fol-

lower 105. This cam makes one revolution for every oscillation of the harnesses 24 and 25.

Where the loom is drawn as shown in Fig. 1, a second or sequence cam 106 is employed because all of the heddles 40 are not elevated at the same time. It, therefore, becomes necessary to test the groups of heddles of the front and rear sets independently. Sequence cam 106 is so timed that lead 107 will be grounded through a double throw switch 108 only when one set of heddles is raised. This condition is shown by the relative position of the plates 37 in Fig. 8. Where both sets of heddles 66 and 67 operate in unison (Fig. 2) switch 109 will be closed so that the ground circuit is conditioned through either lead 110 or 111 simultaneously rather than alternately. Assuming that switch 109 is open, as would be required for the drawing of Fig. 1, then the circuit is conditioned when the switch 103 is closed by cam 104 and the contacts 112 of switch 108 are closed to detect a grounded heddle in the front bank. In the event one or more heddles of the front bank are grounded, relay 101 will be energized to open contacts 100, thus opening the holding circuit for relay 94 which stops motor 90 by breaking the circuit thereto and de-energizing brake solenoid 115 on the motor. This in turn clamps the armature of motor 90 through brake shoes 116. Where all of the heddles 66 and 67 operate in unison, switch 109 will be closed and lead 107 grounded if any one of the stop motion heddles is not raised by its associated pile yarn or yarns. The individual heddles, particularly in the form of Fig. 7, are extremely light and do not affect proper shedding by pile yarn harnesses. The system is extremely versatile and is found to be very effective for use in wide carpet looms using heavy pile yarn.

A modified arrangement for the heddles as well as a slightly modified form of heddle is illustrated in Figs. 9-13 as installed on a conventional loom having an oscillating lay 120 which carries a reed 121. The pile yarns 122 and 123 are supplied from beam 124 and are laced through a tensioning cradle or jumbo 125. The binder warps 126 and 127 are supplied from beam 128 and are tensioned by jumbo 129. The conventional lease rods 130, 130 are used for the binder warps, but the stuffer warps have been omitted in the interests of clarity. The lay 120 is actuated from the loom crankshaft 135 through links 136 and links 137, 138. The woven fabric F is carried over the breast plate 139 by pin take-up roller 140. Pile yarns 122 are drawn through and controlled by harness 141 and pile yarns 123 are controlled by harness 142. Binder warps 126 and 127 are controlled by harnesses 143 and 144 respectively. These harnesses reciprocate vertically to form the various sheds in the weaving operation as described in connection with Fig. 1 and are well known in the art.

The pile yarns 122 and 123 are also threaded through the long slot 150 of a group or series of stop motion heddles 151 positioned closely adjacent the back chain harness 144. Heddles 151 (Fig. 14) are somewhat similar to heddles 36 in that they are equipped with the same contact plate 152 having the biased upper terminus 153. The slot 150 in the heddles 151 is somewhat shorter than the slot 35 in heddles 36 due to the fact that the maximum positions of the shed are spaced closer together in the stop motion position of Fig. 9 than in the position of Fig. 1. The heddles 151 are supported by a contact element 154, which extends through the slots of plates 152 in precisely the same manner as described previously in connection with Figs. 1 and 2. However, the bottoms of heddles 151 carry an elongated slot or eye 155 through which a bar or strip 156 (Fig. 10) is inserted to act as a guide for the heddles.

Figs. 10 and 11 illustrate the details of the construction of the stop motion mechanism of Fig. 9. Upper contact element 154 is secured to the loom frame 157 in brackets 158 and 159. Bar 156 is secured to the loom frame 157 by means of brackets 160 and cotter pins 161.

Brackets 158 and 159 support dielectric blocks 162 and 163 respectively by means of setscrews 164, 164. The blocks support contact element 154 and electrically insulate it from the loom frame. Electrical lead 165 is connected to the contact strip 166 by means of a binding post 167 and insulated bushing 168. The housing 169 is connected to a lead 170 through a setscrew 171 (Fig. 12) having a nut 172. In this manner no ground circuit is used since the housing 169 is completely insulated from the loom frame as well as from the contact strip 166.

In operation, electrical current from a source 175 is carried to transformer 176 through double pole switch 177. High tension current for the loom motor 178 is tapped into leads 179 and 180 through the contacts 181 and 182 of triple contact relay 183. Motor 178 is supplied with a solenoid and toggle-actuated brake similar to that shown in Fig. 8. A solenoid 184 is tapped into the motor line and when de-energized permits the brake shoes 185 and 186 to quickly stop the armature of the motor. The circuit in Fig. 15 is conditioned by means of a cam 190 attached to the shaft 135. A cam follower 191 is positioned to close a switch 192 when depressed by cam 190. This switch is closed when either pile yarns 122 or 123 are in a maximum top shed position, thus holding all of the heddles 151 in an elevated position shown in Fig. 13 so that there is no contact between the biased slot terminus 153 and contact strip 166. As previously described in connection with Fig. 8, a start and stop switch 193 is connected to the low side of transformer 176 through leads 194 and 195. When the start button 196 is depressed, relay 183 is energized through leads 197 and 198. A holding circuit through relay 199 is completed through contacts 200, leads 197, 201, and 202. The coil of relay 199 is connected to housing 169 through lead 170 and to lead 202 through lead 203. It will be apparent that when switch 192 is closed by cam 190, relay 199 which is normally closed will not be energized unless there is a broken pile yarn or slack pile yarn which permits the circuit to be closed by one of the heddles. In the event such condition occurs, relay 199 is energized to open the holding circuit through lead 201, thus opening relay 183 and stopping the motor 178.

In the form of Fig. 9, it will be observed that the yarn travel in the slot in the stop motion heddle 151 is substantially less than is the case with heddle 36. Furthermore, both warps 122 and 123 are drawn through the same heddle 151 so that they cross each other in slot 150. The form of Fig. 9 requires only half as many stop motion heddles as the form of Fig. 1, but under some conditions it may be undesirable to have two pile yarns working in opposite directions in the same heddle slot. Furthermore, it has been found that the construction of Fig. 1 may be more sensitive than that of Fig. 9. In any case the selection of stop motion heddle and its location as well as the particular type of circuit depends on the type and size of the loom as well as the weave of the fabric and the pile yarn being utilized. The device has been found to be accurate, efficient, and requires a minimum of maintenance.

Having thus described our invention, we claim:

1. In a weaving loom having a plurality of shed forming harnesses, a stop motion assembly comprising a series of drop wire heddles for the warp yarns in said loom, an elongated slot in each heddle through which a warp yarn is drawn said slot being of sufficient length to eliminate inter-actuation of the heddle and the warp yarn passing through said slot except when a taut warp yarn is in a fully raised shed position, a support for said heddles adjacent one of said shed forming harnesses, an extension on each of said heddles, and electrical circuit means cyclically connected to said extension on each heddle to complete a circuit and stop the loom in the event the heddle is not elevated when a warp shed is formed to its maximum position.

2. Apparatus in accordance with claim 1 in which the support is positioned in back of the rear shed forming harness.
3. Apparatus in accordance with claim 1 in which the support is located in front of the front shed forming harness.
4. Apparatus in accordance with claim 1 having a guide cable stretched through the bottom of the slot in each heddle and anchored to the loom.
5. In a weaving loom having a plurality of shed forming harnesses, a stop motion assembly comprising a series of drop wire heddles for the warp yarns in said loom, an elongated slot in each heddle through which a warp yarn is drawn said slot being of sufficient length to eliminate inter-actuation of the heddle and the warp yarn passing through said slot except when a taut warp yarn is in a fully raised shed position, a first extension on each of said heddles to maintain the heddles in relative alignment with respect to each other, a stationary support for the heddles adjacent one of said shed forming harnesses, a second extension on each of said heddles, and electrical circuit means cyclically connected to said extension on each heddle to complete a circuit and stop the loom in the event the heddle is not elevated when a warp shed is formed to its maximum position.
6. Apparatus in accordance with claim 5 in which the lower extension comprises a slotted eye, and a bar extending through the slotted lower eye of each heddle and anchored on the loom.
7. Apparatus in accordance with claim 5 in which the lower extension comprises a guide rod.
8. Apparatus in accordance with claim 5 having a guide cable stretched through the bottom of the slot in each heddle and anchored to the loom.
9. In a weaving loom having a plurality of shed forming harnesses, a stop motion assembly comprising a series of drop wire heddles for the warp yarns in said loom, an elongated slot in each heddle through which a warp yarn is drawn said slot being of sufficient length to eliminate inter-actuation of the heddle and the warp yarn passing through said slot except when a taut warp yarn is in a fully raised shed position, a lower extension on each of said heddles to maintain the heddles in relative alignment with respect to each other, a stationary support for the heddles adjacent one of said shed forming harnesses, an upper extension on each of said heddles, and electrical circuit means cyclically connected to said extension on each heddle to complete a circuit and stop the loom in the event the heddle is not elevated when a warp shed is formed to its maximum position.
10. In a weaving loom having a motor and a plurality of shed forming harnesses, a stop motion assembly for a weaving loom comprising a plurality of drop wire heddles mounted in the loom in the shed area, an elongated slot in each heddle of a length determined substantially by maximum and minimum shed positions, guide means for maintaining alignment of said heddles at the bottom of each heddle, a contact element supporting and enclosed by the top of each heddle, a timing cam driven by the loom for conditioning a circuit through the said contact element, and means including relays for stopping the loom motor in the event a heddle remains supported on the contact element when said circuit is conditioned.
11. Apparatus in accordance with claim 10 in which the guide means comprises an extension below the slotted eye.
12. Apparatus in accordance with claim 10 having a plurality of heddles mounted on the loom in front of the front loom harness.
13. Apparatus in accordance with claim 10 having a plurality of heddles mounted on the loom in back of the back loom harness.
14. In a weaving loom the combination which comprises at least two harnesses for forming warps into sheds by alternately raising and lowering warp ends, a

slotted drop wire heddle through which each pair of said warp pile ends is drawn, means supporting each of said heddles adjacent one of said harnesses, and means associated with each of said slotted heddles for stopping said loom when said slotted heddle is not elevated to a predetermined position by one of said warp pile ends when the pile harnesses reverse.

15. In a weaving loom the combination which comprises a reed, means for oscillating said reed from a retracted position to a position adjacent the fell of a fabric being woven in the loom, at least two harnesses for forming warps into sheds by alternately raising and lowering warp ends, a slotted drop wire heddle through which each pair of said warp pile ends is drawn, means supporting each of said heddles between one of said harnesses and

the reed, and means associated with each of said slotted heddles for stopping said loom when said slotted heddle is not elevated to a predetermined position by one of said warp pile ends when the pile harnesses reverse.
